Primary Examiner — Karen S Acker

(57) **CLAIM**

The ornamental design for a fireplace Aloisi, as shown and described.

DESCRIPTION

FIG. 1 is a first front perspective view of a fireplace showing my new and original design;

FIG. 2 is a second front perspective view of a fireplace showing my new and original design;

FIG. 3 is a front elevation view thereof;

FIG. 4 is a left side elevation view thereof; and,

FIG. 5 is a right side elevation view thereof.

The bottom, top and back sides of the fireplace Aloisi form no part of the claimed design. The broken lines and the spaces within the broken lines in the drawings represent unclaimed environmental subject matter.
